UNITED STATES PATENT OFFICE.

DWIGHT ORION BARRETT, OF LIMA, OHIO.

SPRAY-NOZZLE FOR VERTICAL DIESEL ENGINES.

1,368,097.

Specification of Letters Patent.

Patented Feb. 8, 1921.

Application filed July 9, 1919. Serial No. 309,562.

To all whom it may concern:

Be it known that I, DWIGHT O. BARRETT, a citizen of the United States, and a resident of Lima, in the county of Allen and 5 State of Ohio, have invented a new and Improved Spray-Nozzle for Vertical Diesel Engines, of which the following is a full, clear, and exact description.

This invention relates to spray nozzles 10 for the Diesel type of engine and particularly to a vertical engine, and has for an object to provide an improved construction wherein the oil may be sprayed into the engine under any desired pressure without 15 placing the main supply of oil under any appreciable pressure.

Another object of the invention is to provide a spray nozzle for vertical Diesel engines wherein the oil is fed into one section 20 of the nozzle under a comparatively low pressure and then forced under high pressure into the cylinder.

A further object of the invention is to provide a nozzle for Diesel engines in which 25 means are provided for supplying a measured quantity of oil to the engine at intervals, same being mixed with air at a comparatively high pressure.

In the accompanying drawing:

30 Figure 1 is a fragmentary, longitudinal, vertical section through a nozzle embodying the invention and positioned in an engine.

Fig. 2 is a transverse sectional view through Fig. 1 on line 2—2.

35 Referring to the accompanying drawing by numerals, 1 indicates a Diesel engine cylinder of the vertical type through which the nozzle 2 is connected by threads or in any desired manner. The upper or outer 40 part of the nozzle is of any desired construction, as for instance the one now in common use. The shell 3 of the nozzle may be threaded at the end to fasten into the cylinder 1, or may be held against a flange and 45 provided with a gasket, or any other means.

In the same manner the core member 5 may be threaded into the shell 3 or clamped in position in any other suitable manner. The 50 end of the shell 3 is provided with a bore 6 having a threaded section 7 for receiving the spray plug 8 which may have one or a number of apertures 9 merging into a conical shaped cavity 10. The plug 8 may be threaded into the shell 3 or held by any 55 other means in common use. The core 2 is

provided with a comparatively large air bore 11 and a comparatively small oil bore or passageway 12. Should it be found desirable more than one of these oil passageways may be used to secure a better distribution of the oil. The ball 13 acting as a valve is arranged at the end of passageway 12, the same being held in position by a spring 14 supported by an apertured plug 15. The spring 14 is preferably only of sufficient strength to hold the ball 13 normally against its seat, when any slight pressure is brought to bear thereon, as for instance the oil or suction from the engine, the ball will leave its seat so that the oil 70 may flow into the chamber 16 formed from part of the bore 6. Instead of the ball valve as shown in the drawing a bevel seated valve of conventional type may be used, this valve being either mechanically operated or 75 opened by the suction produced by the piston. The air passageway or bore 11 merges into a valve seat 17 against which the tapering end 18 of the rod 19 rests, said tapering end acting as a valve member. The valve 80 seat 17 merges into a small passageway 20 which in turn merges into one or more laterally extending passageways 21 discharging into the chamber 16. The lower end of the core 2 is provided with a reduced projection 22 which carries the passageways 21 and which also is formed with a trapping chamber 23 overlapping the end of the plug 8 which contains the concavity 10.

By this construction and arrangement 90 whenever the valve 18 is closed oil may pass through passageway 12 into chamber 16 and accumulate therein until the valve 18 is raised off its seat whereupon air under high pressure will pass through the passageway 95 21 and into chamber 16 and above the accumulated oil. This air pressure will quickly seat the valve 13 and will at the same time act on the accumulated oil in chamber 16 for blowing the same at a high pressure 100 through the passageway 9 into the combustion chamber of the engine. The oil will be followed immediately by a predetermined volume of air, some of which will be mixed with the incoming oil. To facilitate the 105 more thorough breaking up of the oil and to insure its being mixed with the incoming air the chamber 16 may be filled with small balls giving a large surface over which the oil may spread, or the same result may be 110

accomplished in different ways, as for instance placing a number of projections on the projection 22.

By this construction and arrangement the oil may be maintained at a low pressure, as for instance a slight pressure produced by compressed air, or a pressure produced by the weight of the oil acting under gravity, or by means of a pump. The air, however, must be under high pressure in order to force the oil in at the proper time. It will be noted that the oil is under low pressure and that the oil is not mixed with the air until it enters or begins to enter the cylinder of the engine, and it is therefore not necessary to force the oil into the nozzle against the air pressure maintained in passageway 11.

What I claim is:

1. A spray nozzle for vertical Diesel engines comprising a shell formed with a chamber, a spray plug closing one end of said chamber, said plug having a passageway therethrough, and a central projection extending into the chamber, a core member having a central projection formed with a bore, said bore providing a trap chamber, the projection on the plug fitting into said trap chamber, said core member having also an air passageway leading to the top of said chamber and an oil passageway leading to the top of the chamber, an inwardly opening valve for said oil passageway, and an outwardly opening valve for the air passageway whereby when air under high pressure is admitted the oil valve will be closed and the oil in said chamber will be forced through the passageway in said plug.

2. A spray nozzle for vertical Diesel engines comprising a shell adapted to be vertically positioned, said shell having a reduced bore at the lower end and a threaded section in said reduced bore, a spray plug

having an aperture, said plug being screwed into said threaded section and formed with an upwardly extending projection, the aperture in the plug passing through said projection, a core positioned in said shell formed with a projecting lower end having a bore telescoping over said projection, said core being provided with an air passageway merging into a valve seat, said valve seat merging into a second air passageway leading to the exterior of the projection on said core and discharging into the reduced bore of the shell, said core being provided also with an oil passageway leading into the reduced bore of said shell, and a spring pressed valve acting in a direction away from said plug for closing said oil passageway, and an air valve positioned to engage the seat in said air passageway whereby oil may freely enter the reduced bore of said shell until said valve is unseated whereupon air will pass into said reduced bore and force the oil in the reduced bore through said plug.

3. A spray nozzle for vertical Diesel engines comprising a shell, a plug in the lower end of the shell formed with a reduced top projection, said plug having one or more passageways extending therethrough and through the projection, a core fitting into the shell formed with a hollow projection overlapping the projection on the plug whereby a trap will be produced, said core being provided with a high pressure air passageway merging into the upper part of said trap, and an oil passageway merging into the upper part of said trap, an air valve for controlling the passage of air through said air passageway, and a spring pressed valve acting in a direction away from the plug for closing the oil passageway.

DWIGHT ORION BARRETT.
